ABSTRACT OF THE DISCLOSURE

An automatic winder having a plurality of winding heads that traverse a closed path, monitoring means for monitoring an operating condition of each winding head, means to indicate each winding head individually as it is being monitored by the monitoring means, and accumulating means for accumulating the results of several monitorings of each winding head.

This invention relates to textile machinery and more particularly, to a self-monitoring automatic winder having improved operating efficiency and reliability because of the ease with which latent mechanical defects are identified for the application of corrective maintenance procedures.

Automatic winders in which a plurality of winding heads traverse a path as yarn is transferred from a bobbin to a package are well known in the textile art. A basic feature of such automatic winders is the providing of a plurality of separate and simultaneous winding operations by the plurality of winding heads operating in combination with a common means for handling the series bobbins and packages carried by each winding head. It is because of this basic feature and many other desirable features that automatic winders are regarded in the textile art as being generally efficient and reliable.

However, the efficiency and reliability of such automatic winders is dependent upon the application of proper corrective maintenance procedures to insure that all winding heads are operating properly and that no winding head is inoperative because of a mechanical defect for a prolonged length of time. The application of proper corrective maintenance procedures is relatively easy to achieve with respect to obvious mechanical defects.

However, many mechanical defects are latent in that they are not apparent even though they cause a winding head to malfunction and the application of proper corrective maintenance procedures with respect to such latent mechanical defects has been difficult to achieve with prior art automatic winders. This is because the usual indication of a latent mechanical defect in an automatic winder is the malfunction of winding head in the transfer of yarn from a bobbin to a package and because such a malfunction of a winding head is frequently the result of a cause completely unrelated to a mechanical defect in the winding head such as a broken yarn on the bobbin.

Thus, with prior art automatic winders, malfunctions of a winding head in the absence of an obvious mechanical defect have generally been ignored on the assumption that they were caused by other than a latent mechanical defect in the winding head and corrective maintenance procedures have been applied only when the latent mechanical defect in the winding head became so serious as to be obvious. In the meantime, the latent mechanical defect in the winding head continued to impair the efficiency and reliability of the automatic winder.

The invention disclosed herein overcomes this difficulty with prior art automatic winders in the application of proper corrective maintenance procedures in that it provides a self-monitoring automatic winder in which latent

2

mechanical defects which would impair the efficiency and reliability of the automatic winder if not corrected are conveniently identified. Since latent defects in an automatic winder may be readily corrected by corrective maintenance procedures once they are identified, the invention provides an automatic winder which is readily maintained at full efficiency and reliability at all times.

These improvements in an automatic winder are provided by an automatic winder having monitoring means for monitoring the operating condition of each winding head in a plurality of winding heads during each operating cycle of the winding head and which in combination with an accumulating means for accumulating the operating conditions of each winding head for a plurality of operating cycles permits the cumulative operating condition of each winding head to be readily indicated. The cumulative operating condition of a winding head will reveal a recurring malfunction and since a recurring malfunction of a winding head over a plurality of operating cycles is indicative of a latent mechanical defect in the winding head, the indication of the cumulative operating condition of the winding head which is provided by the invention permits the prompt application of proper corrective maintenance procedures so that the automatic winder provided by the invention is in a state of substantially maximum efficiency and reliability of all times.

These and other features and advantages of the invention will be more clearly understood from the following detailed description and the accompanying drawings in which like characters of reference designate corresponding parts throughout and in which:

FIG. 1 is a schematic top plan view of an automatic winder embodying the invention disclosed herein.

FIG. 2 is an enlarged side elevational view of one of the plurality winding heads included in the automatic winder of FIG. 1.

FIG. 3 is a schematic diagram of a circuit arrangement for that embodiment of the invention disclosed herein.

These figures and the following detailed description disclose a specific embodiment of the invention but the invention is not limited to the details disclosed since it may be embodied in other equivalent forms.

The invention disclosed herein is best understood in terms of an automatic winder 10 such as that generally shown in FIG. 1 having a plurality of winding heads 11 such as that shown in FIG. 2. It will be understood that an automatic winder 10 of this type conventionally includes an oval track 12 formed by an upper rail 13 and a lower rail 14 and around which the plurality of winding heads 11 are moved by chain 15 as yarn 16 is transferred from a bobbin 17 to a package 18. A magazine hopper 19, a goose neck 20, and other components (not shown) serve to provide each winding head 11 with a new bobbin 17 having a yarn end tied to a yarn end of the previous bobbin 17 each time the winding head 11 passes the magazine hopper 19. These and other conventional structural characteristics and the winding operation of the automatic winder 10 will be understood by those skilled in the art.

However, unlike prior art automatic winders, an automatic winder 10 embodying the invention disclosed herein includes a signature unit 21 mounted on each winding head 11, a signature responsive station 22 positioned adjacent the oval track 12 for providing a signature output characteristic of a particular winding head 11 each time the winding head 11 passes the signature responsive station 22, and relay 25 in the motor circuit 45 of each winding head 11 for providing a condition output for each winding head 11 each time the winding head 11 passes the signature responsive station 22. The plurality of signature units 21, the signature responsive station 22, and the plurality of relays 25 together serve to provide a monitoring

means for monitoring the operating condition of each winding head 11 during each operating cycle of the winding head 11 as defined by a complete cycle of motion around the oval track 12. It is this monitoring means in combination with an accumulating means 26 for accumulating the operating conditions of each winding head 11 for a plurality of operating cycles as determined by a plurality of condition outputs and plurality of signature outputs which provides a self-monitoring automatic winder 10 which is readily maintained at maximum efficiency and reliability.

The signature unit 21 which is mounted on each of the plurality of winding heads 11 is best seen in FIG. 2 where it will be seen that each signature unit 21 includes a vertical actuator member 27 attached at its upper end to the lower side 28 of the winding head 11. Each actuator member 27 has a plurality of finger members 29 extending from one side thereof. The signature responsive station 22 is also best seen in FIG. 2 where it will be seen that the signature responsive station 22 includes a vertical support member 30 having a plurality of microswitches 31 mounted along one side thereof. The support member 30 is fixedly positioned on the floor or on a platform 32 adjacent the oval track 12 of the automatic winder 10 so that one or more of the plurality of microswitches 31 is operatively engaged by the finger members 29 extending from the actuator member 27 mounted on each winding head 11 as the winding head 11 moves along the oval tract 12 past the support member 30.

Thus, the plurality of signature units 21 and the signature responsive station 22 are arranged such that during each cycle of motion of each winding head 11 around the oval track 12, one or more microswitches 31 mounted on the support member 30 is engaged by the finger members 29 of the signature unit 21 mounted on the winding head 11. The arrangement of the finger members 29 extending from each actuator member 27 differs in number or position from the arrangement of finger members 29 extending from other actuator members 27 and as a result the passage of each winding head 11 along the oval track 12 past the signature responsive station 22 actuates a microswitch 31 or group of microswitches 31 which is different from the microswitch 31 or group of microswitches 31 actuated by the passage of any other winding head 11.

It is the particular microswitch 31 or group of microswitches 31 which is actuated by the signature unit 21 mounted on each winding head 11 of the automatic winder 10 that provides a signature output from the signature responsive station 21 for each winding head 11 once during each operating cycle of the winding head 11. The signature output is determined by which microswitches 31 are operated and those skilled in the art will understand that the signature output is most conveniently an electrical output representing a binary coded character having that number of binary digits which corresponds to the number of microswitches 31.

This is because an electrical output representing a binary coded character provides a convenient signature input to a conventional computer 40 and permits the computer 40 to be used as an accumulating means 26 for accumulating the operating conditions of each winding head 11 during a plurality of operating cycles. The providing of a signature input to a computer 40 is best shown in FIG. 3 which shows a circuit arrangement in which the microswitches 31 are arranged to provide a plurality of successive inputs to the computer 40 with the nature of each input being determined by which microswitches 31 are operated or not operated. In that embodiment of the invention disclosed herein, there are ten microswitches 31 and it will be understood by those skilled in the art that the binary coded character represented by a signature output from the signature responsive station 22 and by the corresponding signature input to the computer 40 may be any of a plurality of binary coded characters between

0000000000 and 1111111111 and that these binary coded characters correspond to decimal numbers ranging from 0 to 1,023. Thus, in that embodiment of the invention disclosed herein, the finger members 29 of the signature units 21 may be arranged to provide a particular signature output and the corresponding signature input for each of 1,023 winding heads 11 which is different from the signature output of any other winding head 11.

The manner in which the relays 25 provide a condition output is also best understood from FIG. 3 in which it will be seen that the motor circuit 45 of each of the plurality of winder heads 11 includes the coil 46 of a relay 25, but the normally open contact 47 of each relay 25 is in one of a plurality of circuits 70 providing an input to the computer 40. It will be understood that when the motor 48 of a winding head 11 is energized there is a continuous input to the computer 40 corresponding to the particular winding head 11 as a result of the energizing of the coil 46 in the motor circuit 45 of the motor 48 and the closing of a contact 47 by the coil 46. When the motor 48 is not energized, there is no input to the computer 40 corresponding to the winding head 11 and it will now be understood that it is in this manner that the plurality of relays 25 serve to provide a plurality of condition outputs, each of which is a condition input to the computer 40 which is indicative of the operating condition of a particular winding head 11.

A further understanding of the invention disclosed herein is provided by considering the operation of an automatic winder 10 embodying the invention. As is conventional with an automatic winder 10, the plurality of winding heads 11 travel continuously along the oval path 12 to provide for the transfer of yarn 16 from bobbins 17 to packages 18. However, in a self-monitoring automatic winder 10 embodying the invention disclosed herein, each time one of the plurality of winding heads 11 passes the signature responsive station 22, microswitches 31 are actuated by the signature unit 21 carried by the winding head 11. Since the finger members 29 on each signature unit 21 differ in number or arrangement from the finger members 29 on other signature units 21, the passage of the winding head 11 results in particular microswitches 31 being actuated which in turn provides a signature output as a signature input to the computer 40.

The computer 40 is programmed in a conventional manner so that each time a signature input is received from the signature responsive station 22, the computer 40 is operatively responsive to the particular condition input corresponding to the particular winding head 11 identified by the signature input. Moreover, the computer 40 is programmed to record the nature of each condition input in terms of whether the contact 47 in the circuit 70 is open or closed.

It will be understood that it is conventional for each winding head 11 of an automatic winder 10 to be arranged so that the yarn 16 passes from a bobbin 17 over an actuator lever 60 to the package 18 and maintains the actuator lever 60 in operative position as long as yarn 16 is passing between the bobbin 17 and the package 18. However, when a breakage of yarn 16 occurs, the actuator lever 60 is released from operative position and moves to an inoperative position to open the motor circuit 45 to the motor 48 of the winding head 11. Thus, whether the contact 47 of each circuit 70 to the computer 40 is open or closed is dependent upon whether the motor 48 of a particular winding head 11 is operative or inoperative which in turn is dependent upon whether a yarn breakage has occurred between the bobbin 17 and the package 18.

Therefore, in a self-monitoring automatic winder 10 embodying the invention disclosed herein the condition input to the computer 40 each time a winding head 11 passes the signature responsive station 22, is indicative of whether yarn 16 is passing from the bobbin 17 to the package 18 or whether yarn breakage has occurred so that yarn 16 is no longer passing from the bobbin 17 to the pack-

age 18. The computer 40 is programmed in a conventional manner to accumulate those condition inputs which correspond to the signature inputs from each of the plurality of winding heads 11 and to provide a summary of the condition inputs for each winding head 11 for a plurality of operating cycles of the winding head 11.

It will be understood by those skilled in the art that the summary of condition inputs from a winding head 11 which is operating properly will show an occasional operating cycle in which yarn breakage has occurred and the motor 48 is inoperative. However, a winding head 11 which is operating improperly because of a latent mechanical defect will show a high frequency of operating cycles in which the motor 48 of the winding head 11 is inoperative because of yarn breakage. Once such a winding head 11 is identified, proper corrective maintenance procedures may be used to remove the latent mechanical defect so as to maintain the automatic winder 10 at maximum efficiency and reliability.

It will now be understood that computer 40 is only generally shown because the computer 40 and its programming will be readily understood by those skilled in the art once the invention is understood. Those skilled in art will further understand that the computer 40 is only representative of a variety of devices which may be used as an accumulating means 26 for accumulating the condition outputs in an automatic winder 10 having the monitoring means described herein and that regardless of the accumulating means 26 used the self-monitoring automatic winder 10 provided by the invention is readily maintained at maximum efficiency and reliability.

It will be obvious to those skilled in the art that many variations may be made in the embodiments chosen for the purpose of illustrating the present invention without departing from the scope thereof as defined by the appended claims.

What is claimed as invention is:

1. In an automatic winder having a plurality of wind-

ing heads which continuously traverse a closed path as yarn is transferred from a bobbin to a package, monitoring means for monitoring an operating condition of each of said winding heads at least once during each cycle of movement around said closed path so as to provide an output indicative of a faulty operating condition of each winding head, signature means to indicate which of said plurality of winding heads is being monitored by said monitoring means, and accumulating means for accumulating said outputs from said monitoring means for each of said winding heads.

2. An automatic winder according to claim 1 in which said signature means includes a plurality of switches mounted adjacent to said closed path, and actuating means on each of said winding heads to close selected ones of said plurality of switches as the winding head passes said plurality of switches.

3. An automatic winder according to claim 2 in which said selected ones of said plurality of switches closed by an actuating means are different for each of said plurality of winding heads.

4. The automatic winder of claim 3 in which said selected ones of said plurality of switches represent a binary coded character.

5. The automatic winder of claim 4 in which said accumulating means is a computer responsive to said binary coded character.
